Inventor,
Otto Huber:
By *Merrells, Bailey* Attorney

UNITED STATES PATENT OFFICE.

OTTO HUBER, OF NEW YORK, N. Y., ASSIGNOR TO THE EAGLE PENCIL COMPANY, OF NEW YORK.

DESIGN FOR A PENHOLDER.

SPECIFICATION forming part of Design No. 31,222, dated July 18, 1899.

Application filed June 15, 1899. Serial No. 720,706. Term of patent 7 years.

To all whom it may concern:

Be it known that I, OTTO HUBER, of the city of New York, in the county and State of New York, have invented a new and original

5 Design for Penholders, of which the following is a specification, reference being had to the accompanying drawings, in which—

Figure 1 is a perspective view of a penholder embodying my design. Fig. 2 is a 10 cross-section of the same through the flattened and spirally-twisted portion.

The leading feature of the design consists of a series of fins *a*, which extend in spiral course around and longitudinally of the axis of

the penholder, and which give the penholder 15 the appearance of having been flattened and then spirally twisted between its two tubular end portions *b c*. The ribs or fins *a* extend inward to the longitudinal axis of the penholder, as indicated in Fig. 2. 20

What I claim as new, and desire to secure by Letters Patent, is—

The design for a penholder as herein shown and described.

OTTO HUBER.
